UNITED STATES PATENT OFFICE.

LOUIS GUSTAVEL, JR., OF DELPHI, INDIANA.

HAME-TUG.

SPECIFICATION forming part of Letters Patent No. 323,321, dated July 28, 1885.

Application filed March 24, 1885. (No model.)

To all whom it may concern:

Be it known that I, LOUIS GUSTAVEL, Jr., of Delphi, in the county of Carroll and State of Indiana, have invented certain new and useful Improvements in Hame-Tugs; and I do hereby declare that the following is a full, clear, and exact description thereof, reference being had to the accompanying drawings, and to the letters of reference marked thereon, which form part of this specification, in which—

Figure 1 is a side elevation of my improved hame-tug complete. Fig. 2 is a similar view of the plate A detached. Fig. 3 is a side elevation of the leather casing with the loops detached. Fig. 4 is a sectional view of the buckle. Fig. 5 is a similar view of the same, showing a modification. Fig. 6 is a longitudinal section of the tug complete.

20 This invention relates to improvements in hame-tugs, and is specially adapted for attachment to heavy draft-harness.

The invention consists in the construction and novel arrangement of parts hereinafter described, and pointed out in the appended claims.

Referring to the accompanying drawings by letter, A designates a flexible metal plate having the transverse bearings a a formed on its front end, and its rear end, a', reduced in width and provided with the openings a' a'. B is a hame-clip having its rear edge, b, reduced in width for insertion between the bearings a a and provided with a transverse canal, 30 by means of which and the rod b' it is connected with said bearings. The rod b' is fixed in the bearings so that the hame-clip turns on the plate A. The front end of the hame-clip is preferably rounded, and has attached to it 35 by rivet or screw the ring or loop b' for connection to the harness.

The metal plate A is provided with the leather casing C, stitched by its edges thereon, and having on its outer face the two similar 45 rectangular transverse slots or cut-away portions c c. D D are similar loops, which are inserted in the slots c c, and are held therein by sliding the plate A in the casing C so as to pass through said loops.

50 E is a buckle-frame having its upper and

lower arms, e e, curved backward and outward, as shown. The shaft e' of the buckle is surrounded by a strong leather collar, F, the meeting ends of the band forming the collar being chamfered and stitched together so as to 55 form a wedge-shaped projection, f, which enters the rear end of the casing C, the reduced end a' of the plate passing between the layers of the projection f.

G G are riveting-pins which pass through 60 the layers of the casing, the layers of the projection f, and the openings a' a' in the plate A. The heads g of the pins G rest against the inner layer of the casing, and their outer ends project beyond the outer layer of the same 65 and act as tongues to the buckle, entering proper holes in the traces H, as shown.

With heavy draft-harness the collar F has on its interior a strong metal re-enforcing collar, I, which surrounds the shaft e' of the 70 buckle, the extended ends i i of which lie together between the layers of the projection f. The pins G G pass through proper openings in the plates i and take all strain off the surrounding leather. With light hame-tugs this 75 feature of construction may be omitted.

The loops D may be either of leather or metal, as desired.

The above-described construction, while simple, forms a very strong and compact hame-tug and one in which the loops D are very 80 strongly secured in place.

Having thus described my invention I claim—

1. In a hame-tug, the combination, with a 85 leather casing having the loops attached thereto, of a metal plate secured within the casing, and having the clip for attachment to the hames and the buckle for the traces pivoted, respectively, to its front and rear ends, substantially as specified.

2. In a hame-tug, the combination of an interior metal plate carrying the hame-clip and buckle, respectively, on its front and rear ends with an exterior leather casing provided on 95 its outer layer with recesses or cut-away portions in which the sides of the loops are inserted and the loops placed therein, the metal plate passing through the loops and holding them to the casing, substantially as specified. 100

3. In a hame-tug, the combination of the casing C and plate A with the hame-clip B, pivoted to the front end of the plate, the buckle-frame E, collar F, provided with the 5 wedge-shaped projection f, and pins G G, substantially as specified.

4. In a hame-tug, the combination, with the casing C, plate A, buckle-frame E, collar F, provided with the wedge-shaped projection f, and pins G G, of the re-enforcing metal 10 collar I, provided with the plates i, substantially as specified.

5. The combination, in a hame-tug, with the casing C, provided with recesses c c, loops D, and plate A, of the buckle-frame E, collar F, 15 provided with the projection f, and pins G G, substantially as specified.

In testimony that I claim the foregoing as my own I affix my signature in presence of two witnesses.

LOUIS GUSTAVEL, JR.
